UNITED STATES PATENT OFFICE.

PAUL SAGI, OF TRENTON, NEW JERSEY.

CUSPIDOR.

981,479.

Specification of Letters Patent. Patented Jan. 10, 1911.

Application filed August 5, 1910. Serial No. 575,840.

To all whom it may concern:

Be it known that I, PAUL SAGI, a subject of the King of Hungary, residing at Trenton, in the county of Mercer and State of New Jersey, have invented certain new and useful Improvements in Cuspidors, of which the following is a specification, reference being had therein to the accompanying drawing.

10 This invention relates to cuspidors and has for its object to provide a device of such class with means in a manner as hereinafter set forth for closing the mouth thereof when the cuspidor is inverted, thereby preventing 15 the spilling of the contents of the cuspidor.

Further objects of the invention are to provide a cuspidor which shall be comparatively simple in its construction and arrangement, strong, durable, efficient in its 20 use, provided with a weight-operated means in a manner as hereinafter set forth adapted to be automatically shifted to close the mouth of the cuspidor when the latter is inverted, and comparatively inexpensive to 25 manufacture.

With the foregoing and other objects in view, the invention consists of the novel construction, combination and arrangement of parts as hereinafter more specifically described and illustrated in the accompanying drawings wherein is shown the preferred embodiment of the invention, but it is to be understood that changes, variations and modifications can be resorted to which come 35 within the scope of the claims hereunto appended.

In describing the invention in detail, reference is had to the accompanying drawing wherein like reference characters denote corresponding parts throughout the several views and in which:

Figure 1 is a side elevation of a cuspidor in accordance with this invention. Fig. 2 is a vertical sectional view thereof. Fig. 3 is a top plan. Fig. 4 is an elevation of the sealing member for the mouth. Figs. 5 and 45 6 are elevations of the shifting members for the sealing member, and, Fig. 7 is an elevation of the actuating weight and its guide rod therefor.

50 Referring to the drawings in detail, A denotes a receptacle provided with an opening A' centrally of its top A² and through which

extends a depending tube A³ which is carried by a funnel-shaped mouth piece B. 55 Fixed to the bottom A⁴ of the receptacle A, centrally of said bottom, is a vertically-disposed guide rod C provided at its top with a detachable knob D. The rod C extends up into the tube A³. Mounted upon the rod C 60 is a semi-spherical sealing member F which is adapted to be shifted to partially extend into the tube A³ thereby closing the same. The member F is moved to a position to close the tube A³ when the cuspidor is tilted 65 or shifted. The manner in which the member F is moved will be presently referred to. Mounted upon the rod C as well as being slidable thereon is an actuating weight E, which when the cuspidor is in an upright 70 position, is supported upon the bottom A⁴ of the receptacle A. Mounted upon the rod C and inclosing the weight E is a housing H which when the cuspidor is in an upright position protects the weight E. When the 75 cuspidor is tilted, the weight E is adapted to engage the housing H and shift the same on the rod C. Interposed between the housing H or member H is a shifting member G for the member F. The member G is adapted to be engaged by the housing or member H when the latter is shifted. The housing or member H sliding upon the rod C will engage the member G and the latter will be moved to engage the member F whereby 85 said member F will be shifted to partially extend in the tube A³ thereby closing it.

What I claim is:

1. A cuspidor comprising a receptacle having an opening in the top thereof, a funnel-shaped mouth piece provided with a depending tube extending through the opening of the top of the receptacle, a rod connected to the receptacle and extending in said tube, a shiftable means mounted upon said tube 90 and adapted when shifted in one direction to partially extend in the tube and close the same, a pair of members mounted upon the rod for shifting said means, and a weight 95 slidably-mounted upon the rod and adapted when the cuspidor is tilted to engage one of said members thereby shifting the other of said members and said means in one direction to close the tube.

2. A cuspidor comprising a receptacle having an opening in the top thereof, a mouth

piece provided with a depending tube extending through said opening, a rod fixed to the bottom of the receptacle and extending in said tube, shiftable means mounted upon said rod and adapted when moved in one direction to extend in said tube for closing it, and a weight slidably mounted upon said rod and adapted when the cuspidor is

tilted from an upright position to engage said means for shifting it to close said tube. 10

In testimony whereof I affix my signature in the presence of two witnesses:

PAUL SAGI.
